(71) Applicant: **MILREM AS**, Tallinn (EE)

(72) Inventor: **Kuldar Väärtsi**, Tallinn (EE)

(73) Assignee: **MILREM AS**, Tallinn (EE)

(**) Term: **15 Years**

(21) Appl. No.: **35/502,636**

(22) Filed: **Feb. 22, 2017**

(80) **Hague Agreement Data**

Int. Filing Date: **Feb. 22, 2017**

Int. Reg. No.: **DM/095106**

Int. Reg. Date: **Feb. 22, 2017**

Int. Reg. Pub. Date: **Mar. 17, 2017**

(51) **LOC (11) Cl. 12-16**

CLAIM
